DESIGN FOR A WEIGHING SCALE

William H. Greenleaf, Hartford, Conn.

Application March 12, 1935, Serial No. 55,839

Term of patent 14 years

To all whom it may concern:

Be it known that I, William H. Greenleaf, a citizen of the United States and a resident of Hartford, in the county of Hartford and State of Connecticut, have invented a new, original, and ornamental Design for Weighing Scales, of which the following is a specification, reference being had to the accompanying drawing, forming part thereof, in which—

Figure 1 is a top view of a weighing scale showing my new design.

Figure 2 is a side view of the same.

Figure 3 is an isometric view.

I claim—

The ornamental design for a weighing scale, as shown.

WILLIAM H. GREENLEAF.
